Specification for Design.

Patented Dec. 6, 1910.

Application filed July 23, 1910. Serial No. 573,588. Term of patent 7 years.

To all whom it may concern:

Be it known that I, SAMUEL S. SAMPLINER, a citizen of the United States, residing at Cleveland, in the county of Cuyahoga, and State of Ohio, have invented a new, original, and ornamental Design for a Neckscarf or Muffler, of which the following is a specification, reference being had to the accompanying drawing, forming a part thereof.

The figure is a plan view of a neck scarf or muffler, showing my new design.

The knitted neck scarf herein shown is

characterized by end portions of zigzag appearance bordered by plain edges having rounded slightly gathered scallops along the same; the said end portions being connected by a narrower central portion.

I claim—

The ornamental design for a neck scarf or muffler as shown and described.
